Schmidt & Howlett LLP

(57) **CLAIM**

The ornamental design for lazy Susan tiered shelf accessory,
as shown and described.

DESCRIPTION

FIG. 1 is a sectional perspective view, a half shown for ease
of illustration;

FIG. 2 is an exploded perspective view thereof showing both
halves; and,

FIG. 3 is a perspective view thereof.

The broken lines in FIG. 3 are for illustrative purposes only
and forms no part of the claimed design.
